UNITED STATES PATENT OFFICE.

MARY STALDER, OF CHICAGO, ILLINOIS.

DRESSMAKER'S STAND.

1,293,967.

Specification of Letters Patent. Patented Feb. 11, 1919.

Application filed May 11, 1918. Serial No. 233,841.

To all whom it may concern:

Be it known that I, MARY STALDER, a citizen of the Swiss Confederation, residing at Chicago, in the county of Cook and State of Illinois, have invented certain new and useful Improvements in Dressmakers' Stands, of which the following is a specification.

The present invention has to do with certain improvements in dressmakers' stands 10 and the like, such as are used to facilitate the fitting of dresses and skirts.

One of the objects of the invention is to provide a stand or cabinet for this purpose which may, when out of use, be folded up 15 into a very compact structure.

Another object is to provide a cabinet or stand of very simple design and construction and one which can be cheaply produced or manufactured.

Another object is to provide for the accommodation of a chest of drawers within the cabinet, if desired, said drawers, when so used, occupying space which would otherwise be unoccupied or wasted.

Other objects and uses of the invention will appear from a detailed description of the same, which consists in the features of construction and combinations of parts hereinafter described and claimed.

Referring to the drawings:

Figure 1 shows a perspective of the back portion of a cabinet or stand, embodying the features of the present invention, the same being folded up;

Fig. 2 is a perspective view of the stand when opened, looking toward the front portion thereof;

Fig. 3 shows a plan view of the stand in open position;

Fig. 4 shows a front elevation of the stand in closed position;

Fig. 5 shows a fragmentary horizontal section through one of the clips which connect the hem bar to the adjacent vertical post; and

Fig. 6 is a side view corresponding to Fig. 5.

Referring to the several figures, the stand comprises a substantially rectangular cabinet 50 7, having a series of steps 8, 9 and 10, the number depending, of course, upon the height of the stand. Side wings 11 and 12 are hinged to the rear edges of the boxlike structure 7, so that when swung forwardly 55 they may be folded against the side walls

thereof in the manner clearly illustrated in Figs. 1 and 4.

A platform 13 has its front edge hinged to the upper rear edge of the boxlike structure, so that it may be folded over to lie against 60 the top thereof in the manner shown in Figs. 1 and 4, or may be opened out into the horizontal position shown in Figs. 2 and 3 to lie against and be supported upon the wings 11 and 12. When so supported, it will provide 65 a platform of sufficient size to readily accommodate the person whose dress is being fitted.

Ordinarily the treads of the several steps 8 and 9 will project a slight distance beyond the side faces of the cabinet, but certain of them, as well as the risers, should be cut away in the manner clearly illustrated in Fig. 2, to accommodate the wings 11 and 12 when folded forwardly, so that said wings 75 will lie flat against the sides of the cabinet. The wings at such time will lie underneath the tread of the step 10. When the platform 13 is folded forward in the manner shown in Figs. 1 and 4 to lie against the tread of the step 10, its front portion will project beyond said tread. There will then exist between the platform and the wings a space or clearance equal to the thickness of the tread 10. In order to fill in such space, 80 I provide bars or rails 14 and 15 on the side portions of the platform 13, said bars or rails being properly located and of proper size to fill in the space aforementioned in the manner clearly illustrated in Figs. 1 and 4. 90 These bars or rails will also constitute side guards for the platform when it is opened out into operative position.

It is to be observed that a considerable space is contained within the main portion of 95 the cabinet and beneath the several steps 8, 9 and 10. If desired, drawers 16, 17 and 18 may be located in the cabinet, working from the back wall thereof, each drawer being of the maximum size permissible according to 100 the tread beneath which it is produced. If it be not desired to make actual use of this space for this purpose, then blank drawers may be painted or molded into the back wall of the stand so as to give the same a 105 finished appearance when folded up in the manner shown in Fig. 1. In either case, the cabinet or stand will present the appearance of a small chest of drawers.

In order to facilitate the fitting of a skirt 110

and the proper location of the hem on the lower edge thereof, I have provided a pair of side bars 19 and 20 in conjunction with a curved hem bar 21. The side bars are secured to the platform 13, and the hem bar is adjustably connected to the side bars at whatever elevation may be desired. In Fig. 2 only one end of the hem bar is shown as being connected to one of the side bars, the other end of the hem being free. Suitable clips 22 are provided for adjustably connecting the hem bar to the side bars, thumb-screws 23 serving to lock the clips at the correct position on said bars.

When the stand is to be folded up, both ends of the hem bar 21 should be connected into the respective clips 22, and at such time the hem bar should be slid down as close to the platform 13 as possible. Thereupon, when the platform is folded forwardly, the side bars 19 and 20 will move down adjacent to the side portions of the cabinet and close thereto, so that upon folding the wings 11 and 12 forwardly they will lie up close to the side bars as is clearly shown in Fig. 4. It is to be observed in this connection that the width of the cabinet should be substantially the same as the distance between the side bars, and the distance between the side bars should be substantially correct for the convenient manipulation of the skirt during the process of fitting the hem.

The manner in which the hem bar may be used is clearly shown in Fig. 2. It is slid around into one of the clips 22 and released from the other one so as to expose its end portion 24. Then the lower portion of the skirt 25 (which is shown in fragmentary form in Fig. 2) is folded up over the hem bar and basted or pinned along the line of stitching 26, the basting continuing in the direction toward the fastened or secured end of the hem bar, and the basted skirt being gradually slid along the hem bar toward the free or unsecured end thereof, from which the hemmed portion is delivered.

I claim:

1. A stand for the purpose specified comprising, in combination, a cabinet having a series of steps of progressively increasing elevation, a wing hinged to each vertical rear edge thereof and adapted to fold for-

wardly against the corresponding side wall of the cabinet, a platform hinged to the upper rear edge of the cabinet and adapted to fold forwardly over the steps thereof, the platform being of width substantially equal to the overall width measured to the outside surfaces of the wings when they are folded forwardly, and the wings having their upper edges of elevation suitable to support the platform when the wings and platform are extended rearwardly, a guard rail on each side of the platform located in position to align with the corresponding wing when the wings are extended forwardly at the sides of the cabinet and the platform is folded forwardly over the steps, and each guard rail being of vertical dimension substantially equal to the distance between the upper edge of the corresponding wing and the downwardly facing surface of the platform at such time, substantially as described.

2. A stand for the purpose specified comprising, in combination, a cabinet having a series of steps of graduated elevation, a platform hinged to the upper rear edge thereof and adapted to fold forwardly over the steps of the cabinet, a pair of side bars secured to the platform at right angles thereto and substantially in line with the outside surfaces of the cabinet and adapted to closely embrace the cabinet between them when the platform is folded forwardly over the steps aforesaid, and a wing vertically hinged to the rear portion of each side of the cabinet and adapted, when extended rearwardly, to support the platform, and, when folded forwardly, to lie adjacent to the side wall of the cabinet, substantially as described.

3. A dressmaker's stand comprising, in combination, a cabinet having a series of steps of progressively increasing elevation, a platform hinged to the upper edge thereof, a wing vertically hinged to each side of the rear portion of the cabinet and adapted, when extended rearwardly, to support the platform when so extended, and, when folded forwardly against the side wall of the cabinet, to lie beneath the platform when folded forwardly, substantially as described.

MARY STALDER.
